UNITED STATES PATENT OFFICE.

WILLIAM LEE HANLEY, JR., OF BRADFORD, PENNSYLVANIA.

TUNNEL KILN.

Application filed August 30, 1926, Serial No. 132,394. Renewed May 17, 1927.

My invention consists in the novel features hereinafter described, reference being had to the accompanying drawings which illustrate several embodiments of my invention, selected by me for purposes of illustration, and the said invention is fully disclosed in the following description and claims.

My invention relates to tunnel kilns whether of the single or twin tunnel type, and more particularly to the construction and arrangement of the firing zone or zones thereof, whereby the construction of the kiln is greatly simplified and the cost of the same cheapened, while the efficiency of the kiln is increased, and the efficient and intelligent control of the firing zone or zones is greatly facilitated.

My invention also includes certain novel features in the construction and arrangement of parts hereinafter fully disclosed and particularly pointed out in the claims.

In the drawings, Fig. 1, represents a partial horizontal sectional view of a twin tunnel kiln embodying my invention, the end portions of the kiln being broken away.

Fig. 2 represents a vertical transverse section of Fig. 1, on the line 2—2.

Fig. 3 represents a similar section of Fig. 1, on the line 3—3.

Fig. 4 is a view similar to Fig. 2, showing a slight modification.

Fig. 5 is a transverse vertical sectional view through the firing zone of a single tunnel kiln embodying my invention, the section being taken between adjacent furnaces or burners, and showing an arrangement in which the furnaces or burners are located on opposite sides of the firing chamber.

Fig. 6 is a view similar to Fig. 5, showing my invention applied to a single tunnel kiln having furnaces or burners on one side only, the section being taken between adjacent furnaces.

In Figs. 1, 2, and 3, I have shown my invention applied to a double tunnel kiln of the kind described and illustrated in my former application for Letters Patent of the United States, filed October 6, 1923, and given Serial No. 666,880, in which there is a centrally located duplex firing chamber provided with a longitudinally vertical central partition dividing the chamber into two firing zones, each provided with a row of burners or furnaces extending longitudinally thereof, the kiln being provided at

each end of the firing chamber with a unitary end section serving as a combined pre-heating and cooling zone and communicating with both firing zones, two parallel lines of goods transporting means being provided, adapted to convey the goods carried by each, in the opposite direction to the movement of the goods carried by the other, and each extending through both end sections and through one of the firing zones. In these figures, A, represents the duplex firing chamber located centrally with respect to the length of the kiln and provided at opposite ends with a unitary cooling and preheating chamber, one of which is indicated at A¹, and the other at A². The duplex firing chamber comprises the exterior walls 1, 1, a central impervious partition wall, 2, and separate crown, 3, 3, of any usual or preferred construction, forming two tunnels, 4, 4, separated by the partition wall, 2, each of which constitutes a firing zone. At the outer side of each tunnel or firing zone is located a plurality of heating devices for direct firing, which may be of any desired character according to the fuel which it is desired to use. In the present instance, I have shown a plurality of burners indicated at 5, which may be supplied by gas from a main, 6, and air from a pipe, 7, connected with a suitable fan, by means of branch pipes, 8 and 9, respectively, provided with controlling valves. 10 and 11, respectively, so that each of said burners, 5, for each firing zone may be separately regulated. Instead of the burners, 5, I may use a series of furnaces for the consumption of coal or other fuel, and provide suitable means for independently regulating the heat of said furnaces.

Each of the firing zones is provided between the goods space which is indicated at 12, and the outer wall of the furnace, with a longitudinally extending bridge wall, 13, parallel to the outer wall, and forming an inlet passage, 14, between the said walls for the products of combustion from the furnaces which are thus carried upward, as indicated by the arrows in Fig. 2, and discharged downwardly into the adjacent goods space upon and through the goods to be fired, and immediately below the goods space of each firing zone is a longitudinal channel or chamber, 15, to accommodate the cars indicated at 16, which move on rails, 17. These channels or chambers each lie between the lower portion of the bridge wall indi-

cated at 13^a, and the lower portion of the central partition indicated at 2^a, and the partition wall is made of greater thickness at the part 2^a, thereby providing the outwardly inclined shoulders indicated at 2^b, for deflecting the products of combustion across the goods space through the goods towards the adjacent bridge wall. The vertical portions of the inlet passages, 14, adjacent to each furnace are separated from each other by transversely disposed walls or partitions indicated at 18, which connect each bridge wall, 13, with the adjacent exterior furnace wall, 1, as clearly shown in Figs. 1, 10 2, and 3. Each bridge wall, 13, is provided adjacent to the lower portion of the goods space with a plurality of eduction ports or passages indicated at 19, each of which communicates with a transverse passage, 20, extending through the bridge wall, through one of the transverse partition walls, 18, and preferably through the adjacent exterior wall, 1, of the kiln for the purpose of conducting away from the adjacent firing zone 15 the products of combustion from adjacent furnaces or burners under the action of suction obtained as hereinafter described. These eduction passages, 20, are connected with a common eduction flue or header indicated at 21, which is preferably located outside of the kiln structure, and which is preferably located below the level of the kiln floor, (indicated at 22), as indicated for example in Figs. 2 and 3, in which these headers, 21, are shown as located outside of the kiln structure and below and at one side of the kiln. I prefer to locate these headers, 21, below the level of the eduction passages, 20, and to connect the said eduction passages to the header by means of vertical passages, 23.

In the form of kiln illustrated in Figs. 1, 2, and 3, I have shown the vertical passages, 23, located entirely outside of the adjacent kiln wall, 1, and encased in brick work casting indicated at 24, to retain the heat of the products of combustion. The passages, 20 and 23, may be formed directly in the surrounding brick work and lined with fire resisting material, and I have shown them provided with fire clay pipe linings indicated at 20^a and 23^a, respectively. It will be seen that the passages, 20, are located at or slightly above the level of the tops of the tunnel cars in the adjacent firing zone, and the exterior portion of the casings, 24, are preferably each provided with a horizontal exterior passage or aperture indicated at 25, which is preferably of less vertical diameter than the passages, 20 and 23, but of a horizontal diameter equal to or greater than said passages. These apertures, 25, serve a two-fold purpose. In each of said apertures, I prefer to locate a controlling damper which is conveniently made in the form of a block

of fire resisting material indicated at 26, which is adapted to be slid more or less over the vertical passages, 23, to regulate the eduction of gases and products of combustion therethrough and through the adjacent passage, 20. This sliding damper is preferably made of slightly less thickness vertically than the vertical width of the aperture, 25, forming a sighting passage indicated at 27, which will enable an operator on the exterior of the kiln to see through the adjacent passage, 20, the actual condition of the lower courses of goods on the tunnel cars, and as these sighting passages are provided at intervals throughout the length of the firing chamber, the operators can readily determine the proper regulation of the furnaces adjacent to each sighting aperture by observing the color of the lower courses of the goods which at the cooler end of the firing zone will appear black, and at the hotter end will have arrived at incandescence. The outer portion of each of the apertures, 25, is normally closed by a suitable closure indicated at 28. This may be formed in any desired way, but I conveniently employ a block of fire brick fitting said aperture easily, so that it may be removed in order to permit the adjustment of the dampers by a suitable metal implement, or to permit the use of the sighting passage, 27. The downward passage, 23, communicating with each transverse passage, 20, permits of this arrangement just described, and as the products of combustion are withdrawn through these passages, 20 and 23, and the collecting flue or header, 21, by suction, the sighting passages may be safely used, as upon the removal of the closures, 28, air will be drawn in on account of the reduction of pressure in said passages and the flames and hot products will be prevented, by this suction from being projected outwardly through these sighting apertures.

The suction for withdrawing the products of combustion through the eduction ports and passages may be obtained in any desired manner. On account of the high temperature, these products would be likely to injuriously affect a fan if they were drawn through it, and I find it convenient to create this suction by an injector nozzle or nozzles operatively connected with the fan or blower, and discharging a comparatively small stream of air into the collecting pipe or flue, 21, beyond the furnace or into a pipe or flue connected therewith, so as to create the necessary suction. In the present instance in Fig. 1, I have shown by way of example each of the collecting flues, 21, provided with an injector nozzle, 29, connected with a fan, 30, for this purpose. Obviously, both nozzles could be supplied by a single fan or blower, if desired. The eduction flues or passages, 21, may be finally connected with a stack

or uptake discharging into the atmosphere after so much of the heat as is desired, has been recovered, and obviously if the draft of the uptake is sufficient to produce the desired degree of vacuum or suction in the collecting pipes or flues, 21, the size of the injector blowers may be reduced, or they may be disposed with altogether. The hot products of combustion withdrawn from the firing zone will be carried away preferably to some other point where their heat can be recovered and used for some useful purpose, as for heating the air supplied to the furnaces, or for use in connection with the preheating zone by means of a recuperator or otherwise, or for use in connection with the drier. These features, however, form no part in my present invention, and are therefore not herein particularly illustrated or described.

In Fig. 1, I have also shown by way of illustration a fan, 31, connected with each of the air pipes, 7, for supplying air to the burners or furnaces.

In the operation of my improved kiln, the construction of which has just been described, it will be understood that there is a row of cars extending from one end of the kiln to the other, and loaded with brick or other articles to be fired, on each of the tracks, and that in the end sections of the kiln the incoming ware is preheated and water-smoked preferably by means of the fired ware on the cars of the adjacent tracks moving in the opposite direction, so that the preheated ware is brought to a temperature approximately that of the entering end of the firing zone through which it is to pass, by the time it reaches the firing zone. The burners or furnaces will be so regulated as to produce in each firing zone a gradually increasing temperature, or in other words a rising heat curve, the heat curve of one firing zone being the reverse of the heat curve in the other firing zone. By the proper regulation of the controlling valves, 10 and 11, and the eduction valves, 26, these heat curves can be accurately determined and maintained. In the construction previously described, by removing the closures, 28, opposite any one of the eduction ports, 19, the operator can see the exact condition of the bricks or other ware occupying the lowest position on the adjacent car in the adjacent firing zone, and can thus determine the necessary adjustment of the valves and dampers before mentioned, so as to insure that the ware shall be gradually brought to the desired temperature and fired while passing through the appropriate firing zone. The closures, 28, may also be removed for adjusting the sliding dampers, 26, as before stated, and also for the purpose of inserting a pyrometer for the purpose of determining the exact temperature of the adjacent portion of the firing zone. This construction,

therefore, greatly facilitates the efficient operation of the kiln, and greatly contributes to the production of a practically uniform fired product.

In Fig. 4, I have shown a cross-sectional view of the firing chamber of a twin tunnel kiln embodying a slight modification of my invention. To avoid repetition, it may be said that the parts corresponding with those previously described and illustrated in Fig. 3 for example, are given the same numerals in Fig. 4, with the addition of 100. In this instance, the collecting flues, 121, are located outside of kiln proper, but within vertical planes projected downwardly from the exterior of the outer walls of the firing chamber, or in other words beneath the firing chamber. The vertically disposed eduction passages, 123, are therefore connected with the horizontal passages, 120, closely adjacent to the eduction ports, 119, and at the rear end of each of the passages, 120, is a horizontal exterior passage, 125, of less width vertically than the passage, 120, in which is located the sliding chamber or valve, 126. The outer ends of the horizontal passages, 125, are provided with the removable closures, 128, which can be removed to enable the dampers, 126, to be regulated by means of a suitable tool, or for the insertion of a pyrometer above said dampers, or for the purpose of sighting the lower layers of ware on the trucks or tunnel cars at any portion of the adjacent firing zone. The operation of the kiln illustrated in Fig. 4, will be exactly the same as that previously described with reference to Figs. 1, 2, and 3.

In Figure 5, I have illustrated the application of my invention to a single tunnel kiln having the firing chamber thereof provided with a row of burners or furnaces on each side, which may be for example of the type illustrated in Fig. 2. In this instance, the firing chamber is shown as provided with the side walls, 201, and a single crown, 203, a single goods space, 212, for the passage of a single row of tunnel cars, 216, on track rails, 217, located in the usual channel, 215, and the firing chamber is provided in this instance with two bridge walls, 213, forming vertical passages, 218, indicated in dotted lines, for conveying products of combustion from the burners to the space, 204, at the top of the chamber from whence they are directed downward through the goods on the tunnel cars. It is to be understood, that the firing chamber will be heated, and the temperature regulated for the production of a single heat curve by the regulation of the respective burners or furnaces in the same manner as previously described with reference to each of the firing zones, the only difference being that in this instance two oppositely disposed sets of furnaces discharge into the same firing zone. In this

instance, each of the bridge walls, 213, is provided with a longitudinal row of eduction ports, 219, connected by horizontal passages, 220, and vertical passages, 223, with the collecting flues or passages, 221, which may be conveniently connected with each other, and in which suction will be produced in any usual or preferred manner, for example, by the means hereinbefore described 10 of an injector nozzle or nozzles. In this instance, the exterior walls, 201, are provided adjacent to each of the vertical passages, 223, with casings, 224, surrounding the latter to conserve the heat, and these 15 casings are provided with the exterior horizontal passages, 225, in which are located sliding dampers, 226, leaving the sighting apertures, 227, above the same, the passages, 225, being closed by the removable closures, 228, as previously described. By removing 20 the closures, 228, the dampers can be regulated and the lower rows of ware on the trucks can be actually viewed as before described, to assist in the proper regulation 25 of the temperatures within the firing zone, in accordance with the desired heat curve. It will be understood, that instead of locating the collecting passages, 221, and eduction passages, 223, at opposite sides of the firing 30 chamber, they may be arranged in the same manner as indicated in Fig. 4, if preferred.

In Fig. 6, I have shown my invention applied to a single tunnel kiln having its firing chamber provided with a single row 35 of heating furnaces or burners located at one side of the goods space only. In this figure, which represents a sectional view similar to Figs. 3 and 5, through the firing chamber between adjacent furnaces, 301, 40 represents the side walls, 303, the arch or top, 312, the goods space, 316, one of the tunnel trucks or cars on the rails, 317, of the single track. 313, represents the bridge wall located at one side of the goods space, 45 and providing the vertical passages, 318, from the furnaces or burners, indicated in dotted lines at 305, to the space, 304, at the top of the chamber. The bridge wall is provided at intervals along its inner face 50 between adjacent furnaces with eduction ports, 319, communicating with horizontal passages, 320, and vertical passages, 323, with the collecting passage or flue, 321, for withdrawing the products of combustion from the interior of the firing zone. In this instance, as in Fig. 5 the vertical 55 pipes or passages, 323, are located outside of the adjacent kiln wall and protected by casings, 324, in which are located the horizontal exterior passages, 325, the adjustable sliding dampers or valves, 326, providing the sight apertures, 327, above the same, the 60 passages, 325, being closed by the removable closures, 328, in the manner previously described. The operation of the firing chamber

illustrated in Fig. 6, will be the same as previously described with reference to either of the firing zones previously mentioned, and it will be unnecessary to repeat this description. It will be understood, that in the 70 forms of kiln illustrated in Figs. 5 and 6, wherein a single tunnel only is provided, that means will be provided for effecting the preheating and water-smoking of the entering ware before it reaches the firing 75 chamber, but as these features form no part of my present invention, they are not herein particularly illustrated or described. Such preheating and water-smoking may be conveniently effected by passing the hot 80 products of combustion through a recuperator for the purpose of heating air to high temperature, and conducting the hot air into the preheating section of the tunnel kiln.

What I claim and desire to secure by Letters Patent is:—

1. A tunnel kiln having a firing zone located substantially centrally of the length of the kiln, and provided with a longitudinal goods space and direct firing means discharging their products of combustion into the upper portion of the goods space, said goods space being provided at separate points longitudinally and adjacent to its lower portion, with eduction ports, eduction 90 passages connected therewith, and horizontally disposed exterior passages extending in alignment with portions of said eduction ports to the exterior of the kiln to permit the goods in the lower portion of the goods 95 space of the firing zone to be viewed from the exterior of the kiln.

2. A tunnel kiln having a firing zone located substantially centrally of the length of the kiln, and provided with a longitudinal goods space and direct firing means discharging their products of combustion into the upper portion of the goods space, said goods space being provided at separate points longitudinally and adjacent to its lower portion, with eduction ports, eduction 100 passages connected therewith, means for creating suction in said eduction passages, and horizontally disposed exterior passages 105 extending in alignment with portions of said eduction ports to the exterior of the kiln to permit the goods in the lower portion of the goods 110 space of the firing zone to be viewed from the exterior of the kiln.

3. A tunnel kiln having a firing zone located substantially centrally of the length of the kiln, and provided with a longitudinal goods space and direct firing means discharging their products of combustion into the upper portion of the goods space, said goods space being provided at separate points longitudinally and adjacent to its lower portion, with eduction ports, eduction 120 passages connected therewith, and adjustable regulating devices for each of said eduction 125 ports.

tion passages, and horizontally disposed exterior passages extending from each of said eduction passages, adjacent to the controlling devices therefor, and in alignment with 5 a portion of the adjacent eduction port, to the exterior of the kiln, to permit the adjustment of said regulating devices, and to permit the goods in the lower portion of the goods space of the firing zone to be viewed 10 from the exterior of the kiln.

4. A tunnel kiln having a firing zone located substantially centrally of the length of the kiln, and provided with a longitudinal goods space and direct firing means dis- 15 charging their products of combustion into the upper portion of the goods space, said goods space being provided at separate points longitudinally and adjacent to its lower portion, with eduction ports, eduction 20 passages connected therewith, and comprising each a horizontally disposed portion, and a vertically disposed portion communicating therewith, a collecting passage connected with the vertical portions of said eduction 25 passages, a horizontally movable damper for partially closing each of said vertical portions of said eduction passages, a horizontally disposed exterior passage extending from the horizontal portion of each of said 30 eduction passages in alignment with portions of the eduction port connected therewith, and constructed to provide a view of the goods in the lower portion of the goods space of the firing zone from the exterior of the kiln to and permit the operation of said 35 dampers from the exterior of the kiln and movable closing means for said exterior passages.

5. A tunnel kiln having a firing zone located substantially centrally of the length of the kiln, and provided with a longitudinal goods space and direct firing means dis- 40 charging their products of combustion into the upper portion of the goods space, said goods space being provided at separate points longitudinally and adjacent to its lower portion, with eduction ports, eduction 45 passages connected therewith, and comprising each a horizontally disposed portion, extending from one of the eduction ports through the adjacent side wall of the kiln to the exterior of the kiln, and vertically disposed portions communicating therewith, a collecting passage outside of the kiln connected with said vertical portions of said eduction 50 passages, and detachable closing means for the outer ends of said horizontally disposed portions of the eduction passages to provide for viewing the goods in the lower portions of the goods space from the exterior of the kiln.

6. A tunnel kiln having a firing zone located substantially centrally of the length of the kiln, and provided with a longitudinal goods space and direct firing means dis- 55

charging their products of combustion into the upper portion of the goods space, said goods space being provided at separate points longitudinally and adjacent to its lower portion, with eduction ports, eduction 60 passages connected therewith, and comprising each a horizontally disposed portion, extending from one of the eduction ports through the adjacent side wall of the kiln to the exterior of the kiln, and vertically disposed portions communicating therewith, a collecting passage outside of the kiln connected with said vertical portions of said eduction 65 passages, movable dampers located adjacent to the junction of the horizontal and vertical portions of said eduction passages, and movable closures for the outer ends of said horizontal passages to permit the adjustment of said dampers, and to afford a view of the goods in the lower portion of the goods space from the exterior of the kiln. 70

7. In a tunnel kiln, the combination with the firing zone thereof and goods supporting and conveying means movable longitudinally therethrough of a longitudinal bridge wall in said firing zone, providing inlet passages for the products of combustion between said deflecting walls and adjacent side wall of the kiln, discharging over the top of the bridge wall into the goods space, heating means for said firing zone discharging their products of combustion into said inlet 80 passages, transversely disposed partition walls of less height than the interior of the kiln extending from the bridge wall to the side wall of the kiln and located between said adjacent heating means, said bridge wall being provided with eduction ports on its inner face adjacent to the lower portion of the goods space, each of said ports being in alignment with one of said transverse partition walls, and eduction passages connected with said eduction ports and having portions thereof located in said transverse partition walls, for conducting said products of combustion away from the goods space, said bridge wall between adjacent ports and passages being of solid construction and flue- 85 less. 90

8. In a tunnel kiln, the combination with the firing zone thereof and goods supporting and conveying means movable longitudinally therethrough of a longitudinal bridge wall in said firing zone, providing inlet passages for the products of combustion between said deflecting walls and adjacent side wall of the kiln, discharging over the top of the bridge wall into the goods space, heating means for said firing zone discharging their products of combustion into said inlet 95 passages, transversely disposed partition walls of less height than the interior of the kiln extending from the bridge wall to the side wall of the kiln and located between 100

said adjacent heating means, said bridge wall being provided with eduction ports on its inner face adjacent to the lower portion of the goods space, each of said ports being in alignment with one of said transverse partition walls, and eduction passages connected with said eduction ports and having portions thereof located in said transverse partition walls, for conducting said products of combustion away from the goods space, said kiln wall being provided with horizontal passages in alignment with the respective eduction ports, and having openings at their outer ends to permit the goods in the lower part of the goods space to be viewed, and movable closures for said openings.

9. In a tunnel kiln, the combination with the firing zone thereof and goods supporting and conveying means movable longitudinally therethrough of a longitudinal bridge wall in said firing zone, providing inlet passages for the products of combustion between said bridge wall and the adjacent side wall of the kiln, discharging over the top of the bridge wall into the goods space, heating means for said firing zone discharging their products of combustion into said inlet passages, transversely disposed partition walls of less height than the interior of the kiln extending from the bridge wall to the side wall of the kiln and located between said adjacent heating means, said bridge wall being provided with eduction ports on its inner face adjacent to the lower portion of the goods space, each of said ports being in alignment with one of said transverse partition walls, and eduction passages connected with said eduction ports and having portions thereof located in said transverse partition walls, for conducting said products of combustion away from the goods space, said eduction passages comprising horizontal portions communicating with the eduction ports, and vertical portions communicating with the horizontal portions, a collecting flue outside of the kiln connected with said vertical portions of said eduction passages, said kiln being provided with a plurality of horizontally disposed exterior passages each communicating with the horizontal portion of one of said eduction passages, adjacent to its junction with the vertical portion thereof, a horizontally movable damper block for variably closing each of said vertical portions of said eduction passages, said damper blocks being of less vertical width than the said exterior passages, and movable closures for the outer end of said exterior passages, whereby said closures may be moved to permit of the adjustment of said damper blocks, and to permit a view of the goods in the lower portion of said goods space through the apertures formed between the damper blocks, and adjacent walls of said exterior passages.
10. In a tunnel kiln, the combination with the firing zone thereof and goods supporting and conveying means movable longitudinally therethrough of a vertical longitudinal bridge wall in said firing zone providing inlet passages for the products of combustion between it and the adjacent side wall of the kiln, extending over the top of the bridge wall into the goods space, a row of heating means discharging their products of combustion into said inlet passages, traversely disposed partitions of less height than the bridge wall between it and the adjacent side wall of the kiln, said bridge wall being provided with eduction ports on its inner face adjacent to the lower portion of the goods space, transversely disposed eduction passages connected with said eduction ports and extending horizontally through the bridge wall and through said partition walls to the

exterior of the kiln, a vertical eduction passage connected with each of said horizontal passages, a longitudinally extending collecting flue exterior to the kiln connected with said vertical passages, means for creating suction in said collecting flue and passages connected therewith, the outer ends of said horizontal passages being provided with apertures exterior to the kiln in alignment

with the respective eduction ports to permit 10 the goods in the lower portion of the goods space to be viewed from the exterior of the kiln, movable closures for said openings, independent means for regulating each of said heating means, and independent means 15 for regulating each of said eduction passages.

In testimony whereof I affix my signature.

WILLIAM LEE HANLEY, JR.
